UNITED STATES PATENT OFFICE.

BENJAMIN H. JOHNSON AND BENSON M. PHELPS, OF ROANOKE, VIRGINIA; SAID JOHNSON ASSIGNOR TO WILLIAM S. PHELPS, OF BLUEFIELD, WEST VIRGINIA.

BED-FRAME CONNECTION.

1,351,758.

Specification of Letters Patent. Patented Sept. 7, 1920.

Application filed May 27, 1918. Serial No. 236,864.

To all whom it may concern:

Be it known that we, BENJAMIN H. JOHNSON, and BENSON M. PHELPS, citizens of the United States, residing at Roanoke, in the county of Roanoke, State of Virginia, have invented certain new and useful Improvements in Bed-Frame Connections; and we do hereby declare the following to be a full, clear, and exact description of the invention, such as will enable others skilled in the art to which it appertains to make and use the same.

The present invention relates to new and useful improvements in bed structures and is directed more particularly to the provision of means for securing the side rails of a bed frame to the corner posts.

The usual method of securing of the end rails of a bed to the corner posts thereof comprises open socket members adapted to receive and seat lugs substantially circular in cross section and connected with the rails along their inner sides, these lugs being taperingly reduced toward their lower ends to insure a firm engagement of the socket members therewith, preventing any undesired looseness, but this wedging relation is open to considerable objection in view of the difficulty of disengaging the lugs and socket members when it is desired to disassemble the bed, particularly if the bed has been assembled and in use for a considerable length of time.

The object of the present invention is to provide a simple and effective connection for the corner posts and side rail ends of a bed, in which any relative looseness between the parts is prevented, but which permits of ready disassembly when desired.

With the above and other objects and advantages in view, the invention resides more particularly in the novel combination, formation and arrangement of parts herein-after described and particularly pointed out in the appended claims.

In the accompanying drawings:

Figure 1 is a side elevational view of the improved corner posts and side rail connections.

Fig. 2 is a plan view thereof.

Fig. 3 is a horizontal sectional view therethrough on the line 3—3 of Fig. 1.

Fig. 4 is a perspective view of the connection.

Fig. 5 is a perspective view of the side

rail end, with the clamping plate removed.

Referring now more particularly to the drawings, 5 designates a corner post of a bed, and 6 designates one of the side rails thereof, the corner post in the present instance carrying the male member of the connection, and this male member comprises a block 7 having one end face curved transversely throughout to fit against the periphery of the corner posts to which it is secured and formed on the opposite face of the block is a vertically extending lug 8 cylindrical in shape and connected along one side integrally with the face of the block by a web 9, whereby the peripheral portions of the lug at the sides of the web form retaining shoulders 10. At the bottom of the lug the block 7 is provided with a ledge or seat 11. Secured to the side rail 6 is a coupling block 12 having its free end portion cut away on one side and provided at its extremity with a transversely arcuate channel 13 co-operating with a corresponding channel 14 formed transversely in one end of a clamping block 15 to define a substantially cylindrical recess for receiving the lug 8, the channels intersecting the ends of the blocks outwardly of the inner faces of the blocks whereby the outer side of the recess is open to receive the web portion 9.

For securing the clamping block 15 to the coupling block 12, a bolt 16 is provided which projects from the inner face of the coupling block 12 and is passed through the block 15 and has threaded thereon the wing nut 17, it being noted that when the nut 17 is loosened the blocks may be readily detached from the lug 8, while still connected with the bolt, and to hold the block 15 against rotative movement on the bolt, a lug 18 projects from its inner end portion and is engageable in a socket 19 in the block 12. It is noted that when the blocks 15 are clamped on the lug, the clamping block 15 substantially fills the cut away portion of the coupling block 12 to present a neat appearance, the inner face of the blocks being spaced slightly apart to permit a positive clamping engagement of the lug with the recess portions of the block, and both blocks seat on the ledge 11.

An exceedingly simple structure has thus been provided which will positively and rigidly connect adjacent side rail and corner post portions of a bed, and which may be

readily manipulated for disassembly when desired.

What is claimed is:

- 5 The combination with the corner post of a bed having a vertical lug and a seat at the base of the lug, of an angle iron bed rail having a cross-sectionally rectangular end portion that is cut away at one side with a resultant shoulder and a longitudinal face,
- 10 10 there being a vertically extending channel in said face at its free end portion and there being a socket in said face adjacent its inner end portion, a stud bolt projecting from said face between the channel and the
- 15 15 socket, a clamping block disposed removably against said face with one end against

the shoulder, the inner face of the opposite end portion of the block having a vertical channel in coöperative relation to the first named channel and receiving with it the 20 lug of the post, the block having a lug removably engaged in said socket and having an opening through the block from which the stud bolt projects, and a clamping nut upon the stud bolt beyond the block. 25

In testimony whereof we affix our signatures in the presence of two witnesses.

BENJAMIN H. JOHNSON
BENSON M. PHELPS.
